UNITED STATES PATENT OFFICE.

RICHARD LEDDICOAT WEARNE, OF BINGHAMTON, NEW YORK.

WASHING-MACHINE.

1,147,285.

Specification of Letters Patent. Patented July 20, 1915.

Application filed March 18, 1915. Serial No. 15,222.

To all whom it may concern:

Be it known that I, RICHARD L. WEARNE, a citizen of the United States, residing at Binghamton, in the county of Broome and State of New York, have invented a new and useful Washing Machine, of which the following is a specification.

This invention relates to washing machines of that type utilizing a motor as an operating means, one of the objects of the invention being to provide a trough or container having a novel form of corrugated bottom whereby the cleaning of the fabrics is expedited, there being a means combined with the tub for deflecting water downwardly onto the fabrics to further assist in the cleaning operation.

A further object is to provide a tub or container having means for imparting both an oscillating and a swinging or tilting movement thereto.

A further object is to provide means whereby the tub or container can be readily coupled to or uncoupled from its actuating means.

A further object is to provide yieldable means connected to the tub or container through its actuating means whereby a balance of the tub is effected.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawing: Figure 1 is a front elevation of a washing machine embodying the present improvements, one of the positions of the tub being indicated by dotted lines and a portion of the gear case being broken away. Fig. 2 is a front elevation of the structure shown in Fig. 1. Fig. 3 is a vertical longitudinal section through the tub of the washer. Fig. 4 is a perspective view of one of the spiders used on the tub. Fig. 5 is a perspective view of the actuating lever and a portion of its drive mechanism. Fig. 6 is a perspective view of one of the tub supporting arms, a portion thereof being

broken away. Fig. 7 is a longitudinal section through the lower end portion of said arm and showing the coupling pin, the means for shifting the same, and the actuating lever in elevation. Fig. 8 is a perspective view of the lever of the coupling pin. Fig. 9 is a plan view of one of the anchoring links. Fig. 10 is a detail view of one of the adjustable supports used in connection with the machine. Fig. 11 is a side elevation of the structure shown in Fig. 10.

Referring to the figures by characters of reference 1 designates a suitable frame which may be provided with an upstanding structure 2 for supporting a wringer mechanism indicated generally at 3. As this mechanism does not constitute any part of the present invention it has not been shown in detail.

Extending transversely of and journaled within the frame 1 close to the bottom thereof is a shaft 4 on which an upstanding lever 5 is closely mounted so as to oscillate freely on the shaft. This lever is connected by a pitman 6 to a drive disk 7 secured to and rotating with the shaft 8 of a gear 9. Said gear is preferably arranged in a housing 10, said housing likewise containing a worm 11 which serves to drive gear 9. Said worm is arranged on a shaft 12 provided with a pulley 13 which receives motion through a belt 14 from a motor 15. Thus it will be seen that during the actuation of the motor, the lever 5 will be oscillated on the shaft 4. As shown particularly in Fig. 5, the upper end of the lever is provided with an aperture 16 and with oppositely extending articulate arms 17, these arms being concentric with the shaft 4.

Secured to the shaft 4 adjacent each end is an upwardly extending supporting arm 18 provided, at its upper end, with oppositely extending arms 19. One of these arms 18 is provided on its outer face with a guide sleeve 20 the upper portion of which is cut away as at 21. In this guide sleeve is mounted a slideable pin 22 designed normally to project into the opening 16, thus to couple the lever 5 to one of the arms 18 so that during the oscillation of lever 5, the two arms 18 and the transverse shaft 4 will be actuated. That portion of the pin 22 exposed within the recess 21 is provided with an annular groove 23 into which projects the lower end of a broad arm 24 the lower edge 119 of which is curved along a line concentric with the shaft 4. This arm 24 constitutes

the lower portion of the lever 25 which is fulcrumed as at 26 upon the frame 1. By providing the arm 24 with the arcuate edge indicated at 27, said arm will remain seated 5 within the groove 28 at all times during the oscillation of arm 18 so that, at any time during such oscillation, the lever 25 can be actuated for the purpose of shifting the pin 22 out of engagement with the lever 5, thus 10 uncoupling said lever from the arm 18.

Each of the arms 18 is provided at its upper end with an opening 28 and these openings are designed to receive trunnions 29 extending from spiders 30 which are secured to the flat sides of a tub or container 31. The bottom of each spider 30 is pivotally connected to an anchor having a link 32 which, in turn, is pivotally connected to the top portion of the frame 1. Ears 33 are 20 extended outwardly from the ends of the spiders and coiled springs 34 connect these levers to the adjacent arms 19.

The tub or container 31 has rounded end walls 35 merging, at their upper ends, into 25 downwardly and inwardly curved deflectors 36, these deflectors being spaced apart by a depressed top portion 37 designed to support a closure 38. The bottom of the tub or container is made up of transverse angular corrugations 39 extending downwardly from the center of the bottom to the lower end of the rounded end walls.

For the purpose of holding the washing machine against movement while in operation, an eccentric 40 is mounted on each corner portion of the frame 1, each of these eccentrics being connected to the upper end of a slide 41 mounted in suitable guides 42. Each eccentric has a handle 43 whereby it 35 can be rotated readily. By moving the handle in one direction, the slide 41 will be pushed downwardly, thus engaging the surface on which the washing machine is mounted and lifting the supporting wheels or 40 casters 44 of the machine out of contact with said surface. The points of connection between the slides 41 and eccentrics are adapted to be moved past the dead centers so that the parts will lock when lowered in the manner described. When the parts are thus 45 adjusted the handles 43 come against stop shoulders 45 in the paths thereof and as shown in Fig. 10.

In using the machine herein described the 55 fabrics to be cleaned are placed in the tub or container 31 with a suitable supply of cleansing fluid, such as soapy water. If the pin 22 is out of engagement with lever 5, the motor can be put in operation and this will 60 cause oscillation of lever 5 without corresponding movement of the arms 18 and tub 31. During this oscillation the arms 17 work back and forth over the ends of the pin 22 so as to prevent said pin from moving 65 into the path of the lever 5. When the

tub is to be coupled to its actuating mechanism lever 25 is shifted so that arm 24 will thrust pin 22 against the upper end portion of lever 5 until the opening 16 is brought into alignment with the pin whereupon said pin 22 will move into the opening. This will result in coupling the lever 5 to the adjacent arm 18 and, consequently, transmitting motion from the motor to the tub 31. When the arms 18 are swung in one direction they 75 transmit motion through the trunnions 29 to the tub, thus causing the tub to swing about its connection with the anchoring links 32 so that the tub is given both a swinging and oscillating movement which results in the liquid contents of the tub being dashed up along one of the curved end walls 35 to the deflector 36 and thence downwardly onto the contained fabric and, on the return stroke, against the other end 80 wall 35 and deflector 36. During this movement the fabrics are caused to travel over the corrugated bottom 39 so that they will be thoroughly rubbed while subjected to the action of the agitated liquid. The springs 85 34 operate to balance the tub during this operation, it being apparent by referring to Fig. 1 that when the tub 31 is swung about its connection with the links 32 one set of springs will be placed under stress. The two 90 sets of springs thus operate to hold the tub 95 yieldingly in balanced position.

The belt indicated at 46 is employed for transmitting motion to the wringer mechanism from a pulley 47 rotating with shaft 8. 100 This, however, constitutes no part of the present invention.

What is claimed is:—

1. A washing machine including a tub, swinging supports pivotally engaged thereby, and a pivoted anchoring means connected to the tub, the connections between the tub and support and anchoring means being superposed.

2. A washing machine including a tub, a fixed structure, anchoring links connecting said structure to the tub, supporting means pivotally connected to the tub, and means for actuating the supporting means to swing the tub bodily and to oscillate it about its anchoring links.

3. A washing machine including a fixed structure, a tub, anchoring means pivotally connected to the tub and fixed structure, supporting means mounted for oscillation and pivotally connected to the tub, and means for actuating the supporting means to swing the tub bodily therewith, said anchoring means constituting means for swinging the tub about its connection with its support during such bodily movement.

4. A washing machine including a fixed structure, a tub, anchoring means pivotally connected to the tub and fixed structure, supporting means mounted for oscillation and

5 pivotally connected to the tub, and means for actuating the supporting means to swing the tub bodily therewith, said anchoring means constituting means for swinging the tub about its connection with its support during such bodily movement, and yieldable balancing means connecting the supporting means to the tub.

10 6. A washing machine including a tub, a fixed structure, anchoring links pivotally connecting the bottom portion of the tub to the fixed structure, supporting members mounted for oscillation about a fixed pivot below the tub, pivotal connections between the tub and the supporting members at points above the links, and means for actuating said members.

15 7. A washing machine including a tub, a fixed structure, anchoring links pivotally connecting the bottom portion of the tub to the fixed structure, supporting members mounted for oscillation about a fixed pivot below the tub, pivotal connections between the tub and the supporting members at points above the links, and means for actuating said members, and balancing means connecting said members to the shaft.

20 8. A washing machine including a tub, a fixed structure, anchoring links pivotally connecting the bottom portion of the tub to the fixed structure, supporting members mounted for oscillation about a fixed pivot below the tub, pivotal connections between the tub and the supporting members at points above the links, means for actuating said members, balancing means connecting said members to the shaft, said members being extended in opposite directions from the members.

25 9. A washing machine including a fixed structure, a tub, supporting members mounted for oscillation about a fixed pivot below the tub, pivotal connections between said members and tub, oppositely extending yieldable connections between said members and the tub, and a pivoted anchoring means connected to the tub and the fixed structure.

30 10. In a washing machine the combination with a tub, of means for imparting a combined swinging and oscillating movement to the tub, said means including supporting members mounted for oscillation about a fixed pivot below the tub, a pivotal connection between said members and the tub, a fixed structure, an anchoring means pivotally connected to the fixed structure and to the supporting member, and means for oscillating said supporting member.

35 11. In a washing machine, a tub, means for oscillating the tub bodily about a point therebelow, and means for effecting the rocking of the tub during such oscillation.

40 12. In a washing machine, a tub, supports therefor mounted for oscillation, said tub being pivoted to the support, a connection

between the supports for causing the supports to move together, a lever mounted for oscillation about the axis of movement of the supports, means for oscillating said lever, and means under the control of an operator 70 for coupling said lever to and uncoupling it from one of the supports.

45 13. A washing machine including up-standing supports movable together about a common axis, a tub supported thereby, a lever mounted for oscillation about the axis of movement of the support, motor driven means for actuating the lever, and means under the control of an operator for coupling said lever to and uncoupling it from one of 80 the supports during the action of the lever.

50 14. A washing machine including supports mounted for oscillation, said supports being movable together, a tub carried by the supports, a lever mounted for oscillation about 85 the axis of movement of the supports, said lever having an aperture and oppositely extending arms adjacent the aperture, a coupling pin slidably mounted within one of the supports, means for oscillating the lever to move the aperture therein into and out of alignment with the coupling pin, the arms on said lever constituting means for holding the pin against movement in the path of the lever, and means under the control of the operator for shifting the pin into the aperture of the lever during the oscillation of said lever to couple the lever to the support.

55 15. A washing machine, the combination with supports mounted for oscillation, said supports being movable together, and a tub carried by the supports, of a lever mounted for oscillation about the axis of movement of the supports, said lever having 100 an aperture and oppositely extending arms adjacent the aperture, and means for oscillating the lever, a coupling pin slidably mounted in one of the supports, said arms on the lever constituting means for holding the pin against movement into the path of the lever, and a controlling lever slidably engaged at all times by the pin and constituting means for shifting the pin into the aperture in the lever to couple the lever to 105 the support, said controlling lever having 110 an elongated pin engaging arm concentric with the axis of movement of the support and oscillating lever.

60 16. A washing machine including supports mounted for oscillation and movable together, a tub carried by the support, an oscillating lever mounted for movement about the axis of the movement of the support, a coupling element movably mounted on one of the supports, a controlling lever held against movement with the support and having one end slidably engaged at all times by a portion of the coupling means, said end of the controlling lever being concentric with 115 120 125 130 135 140 145 150 155 160 165 170 175 180

- the axis of movement of the support and said controlling lever constituting means for shifting the coupling means into and out of engagement with the oscillating lever.
- 5 16. A washing machine including supports mounted for oscillation and movable together, a tub carried by the support, an oscillating lever mounted for movement about the axis of the movement of the support, a coupling element movably mounted on one of the supports, a controlling lever held against movement with the support and having one end slidably engaged at all times by a portion of the coupling means, said 10 end of the controlling lever being concentric

with the axis of movement of the support and said controlling lever constituting means for shifting the coupling means into and out of engagement with the oscillating lever, and means upon said oscillating lever for holding the coupling means out of the path of the lever. 20

In testimony that I claim the foregoing as my own, I have hereto affixed my signature in the presence of two witnesses.
